LEATHER STAKING MACHINE

William B. Quinn, Philadelphia, Pa.

Application September 16, 1940, Serial No. 357,055

14 Claims. (Cl. 149—14)

This invention relates to leather staking machines, that is to say to apparatus adapted to assist in stretching hides and skins for the purpose of making the same more flexible and pliable, and for improving the shape of the same.

In the manufacture of leather from hides and skins, after the same are subjected to certain of the preliminary treatments, the same are in a hard and stiff condition, and it is well known that if the hides and skins, when in this condition, are stretched in all directions, the same will be rendered soft and pliable and, at the same time, the hides and skins may be brought to a shape more nearly approaching a rectangle, resulting in less loss in the subsequent cutting of the leather for utilization in various articles.

Heretofore no satisfactory machines have been devised for carrying out the staking operation and the same has usually been done largely by hand, requiring a considerable expenditure of energy by the operator as he draws the leather over a straight edge while pulling and stretching the same in the desired directions.

The principal object of the present invention is to provide a machine to assist the operator in carrying out the staking operation, which machine is so constructed and arranged as to greatly minimize the amount of effort required on the part of the operator.

A further object of the invention is to provide a machine of the character aforesaid, by means of which the staking operation will be more efficiently carried out, a more uniform stretching of the skins will be obtained, and the same brought to a more desirable shape, than is possible by means of the hand operations and machines heretofore available.

A further object of the invention is to provide a machine of the character aforesaid which will be readily adaptable for use in the manipulation of hides and skins of various shapes and sizes.

A further object of the invention is to provide a machine of the character aforesaid in which the degree of force on the area of the skin operated upon may be readily and conveniently controlled by the operator, the action being, to a large extent, automatic.

The nature and characteristic features of the invention will be more readily understood from the following description, taken in connection with the accompanying drawings forming part hereof, in which:

Figure 1 is a vertical central section of a leather staking machine embodying the main features of the present invention;

Fig. 2 is a top or plan view thereof; and
Fig. 3 is a horizontal section thereof, taken approximately on the line 3—3 of Fig. 1.

It should of course be understood that the description and drawings herein are illustrative merely, and that various changes and modifications may be made in the structure disclosed without departing from the spirit of the invention.

10 Referring to the drawings, in the particular embodiment of the invention therein shown, 5 is a frame having a table top 6. A shaft 7 is journaled in suitable bearings carried by the frame. The shaft 7 is driven in any suitable manner as, for example, by means of the pulley 8 mounted on one end thereof. The shaft 7 has a drum 9 mounted thereon. The shaft 7 and the drum 9 are so positioned that the drum 9 extends upwardly through an opening 10 in the table top 6. The drum 9 is provided on its periphery with a plurality of suitably spaced blades 11 extending transversely, and secured to the drum in any desired manner.

15 The table top 6 also has mounted thereon a pair of upwardly extending bracket members 12. Extending from each of said bracket members 12 is a forwardly projecting arm 13, the rear end of which is pivotally connected as at 14 to an extension 15 of the upper portion of the bracket member 12. Each of the arms 13 is supported intermediate its ends by a brace member 16, one end of which is pivotally connected, as at 17, to said arm 13. The other end of said brace member 16 is adapted to be adjustably connected to 20 the bracket member 12 by means of a pin 18, which may be selectively mounted in any one of the several apertures 19 provided on a portion of the bracket member 12. The foregoing arrangement is such that the arms 13 may be raised or lowered for a purpose to be presently explained.

25 The forward end of each of the arms 13 is provided with a downwardly extending portion 20 having a slot 21 in which is positioned a bushing 22. The bushings 22 are carried on the ends of a shaft 23 upon which a pulley 24 is mounted. The pulley 24 is of a width corresponding to that of the drum 9 and a belt 25 of similar width extends over the pulley 24 which is disposed 30 toward the front of the machine. Said belt 25 also extends over a pulley 26 which is disposed toward the rear of the machine. The pulley 26 is mounted on a shaft 27. The pulley shafts 23 and 27 are journaled in portions of a movable 35 frame 28. The ends of the shaft 27 also extend

through the lower ends of links 29, the upper ends of which are supported on a transverse shaft 30. The shaft 30 is journaled in suitable bearings 31 carried at the upper ends of the bracket members 12.

The main shaft 7 is also provided with a pulley 32 over which a belt 33 extends. The belt 33 also passes over a pulley 34 for the purpose of driving the same when the main shaft 7 is rotating. The pulley 34 is mounted on a transverse shaft 35 provided at the rear of the frame work. The shaft 35 is journaled in suitable brackets 36 carried by the frame 5. The shaft 35 is also provided with a pulley 37 over which a crossed belt 38 extends. The crossed belt 38 also passes over a pulley 39 which is mounted on the shaft 39 at the top of the machine. The upper shaft 30 is also provided with a pulley 40 over which a belt 41 extends. The belt 41 passes to and drives a pulley 42 mounted on the shaft 27 upon which the pulley 26 for the operating belt 25 is mounted.

The foregoing arrangement is such that when the drum 9 is rotated, the operating belt 25 will be simultaneously rotated, and at the same speed as that of the periphery of the drum 9. The movable frame 28, which supports the operating belt 25, is provided with rearward extensions 43, which are connected by links 44 to rods 45. Each of said rods 45 is pivotally connected, as at 46, to a lever 47 which is mounted on the under side of the table top 6 and pivoted thereto as at 48. Each of said levers 47 has its other end pivotally connected, as at 49, to a rod 50 which extends forwardly to the front of the machine. A transverse bar 51 is carried at the forward ends of said rods 50, said bar being normally spaced a sufficient distance in front of the frame to permit the operation, as will be presently explained.

The foregoing arrangement is such that when pressure is imparted to the transverse bar 51 and the same pushed inwardly, the movable frame 28 which carries the operating belt 25 will be pushed forwardly, the movement of the frame 28 being guided by means of the links 29 at the rear, and the slots 21 in the front ends of the forwardly projecting arms 13.

At the forward end of each side portion of the movable frame 28 there is provided an eye bolt 52, and a similar eye bolt 53 is provided at the top of each bracket member 12. Coil springs 54 extend between the eye bolts 52 carried at the front end of the movable frame 28 and the eye bolts 53 carried by the bracket members 12. The springs 54 serve to return the frame 28 to the inoperative position whenever the pressure on the transverse bar 51 at the front of the machine is released.

To keep the operating belt 25 at all times under proper tension, and yet permit the same to engage a considerable number of the edges of the blades 11 carried by the drum 9, as more particularly hereinafter pointed out, there are provided a pair of tension rollers 55 which are carried by suitable links 56, pivoted as at 57 to lugs 58 projecting upwardly from the frame 28. Coil springs 59 extending between the links 56 cause the slack in the belt 25 to be automatically taken up when required yet at the same time permit the top span of the belt 25 to be straightened out when the extra length is required as the lower span of the belt 25 engages the blades carried on the periphery of the drum 9.

The operation of the device may now be explained.

The machine is started by the application of power to the main shaft 7, the parts being in the positions shown in Fig. 1 of the drawings, whereupon the operator places a portion of the skin over the rotating drum 9 and also places another portion of the skin against the transverse bar 51. Upon pressure being applied by the body of the operator to the bar 51, with the skin extending thereover, the movable frame 28 is moved forwardly by the action of the rods 45, levers 47, and rods 50. When this is done, the front end of the frame 28 is guided by the slots 21 in the forward end of the arms 13. The rear end is similarly controlled by the links 29 through which the shaft 27 extends.

By the foregoing action the lower span of the operating belt 25 will be brought down over the periphery of the drum 9, gripping the portion of the skin which lies therebetween, thus pulling the same to stretch and manipulate it. It will be noted that the greater the pressure applied to the transverse bar 51, the greater will be the gripping action of the operating belt 25 on the portion of the skin which passes over the edges of the blades 11 of the rotating drum 9. The action proceeds by successively placing different portions of the skin between the operating belt 25 and the edges of the blades 11 which are carried on the drum 9, the pressure being released at this point whenever the pressure against the bar is relieved for the purpose of shifting the skin to a new position.

It will of course be apparent that various skins will require treatment to a different extent, and for this purpose the forwardly extending arms 13 may be lowered by changing the location of the lower end of the brace arm 16, placing the pins 18 in the desired apertures 19 in the lower portions of the bracket members 12. In this manner varying positions of the operating belt with respect to the drum are obtainable as are indicated in dotted lines in Fig. 1 of the drawings.

It should be noted that the blades 11 carried by the drum 9 are relatively close to each other so that there will be no tendency of the blades 11 to cut the skin as it is gripped for the purpose of stretching the same. However, these blades 11 will also serve to remove any flesh portions which may be remaining on the skin at the time it is subjected to the staking operation in the machine.

I claim:

1. A leather staking machine comprising a rotating drum, an operating belt adapted to be brought into proximity to the periphery of said drum thereby to grip a portion of the skin being operated upon, and means including a member positioned to be engaged by another portion of the skin and adapted upon having pressure imparted thereto to bring said belt into operative relationship with said drum, said member being movable inwardly toward the drum when pressure is imparted thereto.

2. A leather staking machine comprising a rotating drum, an operating belt adapted to be brought into proximity to the periphery of said drum thereby to grip a portion of the skin being operated upon, means for driving said belt at substantially the same speed as the periphery of said drum, and means including a member positioned to be engaged by another portion of the skin and adapted upon having pressure imparted thereto to bring said belt into operative relationship with

said drum, said member being movable inwardly toward the drum when pressure is imparted thereto.

3. A leather staking machine comprising a rotating drum, an operating belt adapted to be brought into proximity to the drum thereby to grip a portion of the skin being operated upon, and means for bringing said belt into operative relationship with said drum including a transverse bar at the front of the machine over which another portion of the skin extends thereby to stretch the intermediate portion of the skin, said transverse bar being movable inwardly toward the drum when pressure is imparted thereto.

4. A leather staking machine comprising a rotating drum, an operating belt adapted to be brought into proximity to the periphery of said drum thereby to grip a portion of the skin being operated upon, means for driving said belt at substantially the same speed as the periphery of said drum, and means for bringing said belt into operative relationship with said drum including a transverse bar at the front of the machine over which another portion of the skin extends thereby to stretch the intermediate portion of the skin, said transverse bar being movable inwardly toward the drum when pressure is imparted thereto.

5. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, and means including a member positioned to be engaged by another portion of the skin to bring said belt into operative relationship with said drum when pressure is applied to said member, said member being movable inwardly toward the drum when pressure is imparted thereto.

6. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, and means including a member engaged by another portion of the skin for shifting said frame to bring said belt into operative relationship with said drum, said member being movable inwardly toward the drum when pressure is imparted thereto.

7. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, and means including a member engaged by another portion of the skin for shifting said frame to bring said belt into operative relationship with said drum, said member being movable inwardly toward the drum when pressure is imparted thereto.

8. A leather staking machine comprising a ro-

tating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, resilient means for retracting said belt to an inoperative position, and means including a member engaged by another portion of the skin for shifting said movable frame to bring said belt into operative relationship with said drum, said member being movable inwardly toward the drum when pressure is imparted thereto.

9. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, resilient means for retracting said belt to an inoperative position, means including a member engaged by another portion of the skin for bringing said belt into operative relationship with said drum, said member being movable inwardly toward the drum when pressure is imparted thereto and means for adjusting the means for supporting and guiding the belt carrying frame thereby to vary the extent of possible engagement of the belt with the periphery of the drum.

10. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, resilient means for retracting said belt to an inoperative position, and means for bringing said belt into operative relationship with said drum including a transverse bar at the front of the machine over which another portion of the skin extends thereby to stretch the intermediate portion of the skin, said transverse bar being movable inwardly toward the drum when pressure is imparted thereto.

11. A leather staking machine comprising a rotating drum having transversely disposed blades closely arranged on the periphery thereof, said blades being disposed substantially parallel to the axis of the drum, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, resilient means for retracting said belt to an inoperative position; means for bringing said belt into operative relationship with

75 said drum comprising an inwardly movable trans-

verse bar at the front of the machine over which another portion of the skin extends, and link work connecting said transverse bar and the belt carrying frame thereby to stretch the intermediate portion of the skin when pressure is applied to said bar.

12. A leather staking machine comprising a rotating drum having transversely disposed blades closely arranged on the periphery thereof, an operating belt adapted to be brought into proximity to the drum thereby to grip a portion of the skin being operated upon, means for driving said belt at substantially the same speed as the periphery of said drum, a movable frame carrying said belt, means for supporting and guiding said frame to bring said belt to various positions, resilient means for retracting said belt to an inoperative position; means for bringing said belt into operative relationship with said drum comprising an inwardly movable transverse bar at the front of the machine over which another portion of the skin extends, and link work connecting said transverse bar and the belt carrying frame thereby to stretch the intermediate portion of the skin when pressure is applied to said bar; and means for adjusting the means for supporting and guiding the belt carrying frame thereby to vary the extent of possible engagement of the belt with the periphery of the drum.

13. A leather staking machine comprising a rotating drum, an operating belt adapted to be

brought into proximity to the drum thereby to grip a portion of the skin being operated upon, a movable frame carrying said belt, means for supporting and guiding said frame to bring said belt to various positions; and means for bringing said belt into operative relationship with said drum comprising an inwardly movable transverse bar at the front of the machine over which another portion of the skin extends, and a connection between said transverse bar and the belt carrying frame thereby to stretch the intermediate portion of the skin when pressure is applied to said bar.

14. A leather staking machine comprising a rotating drum, an operating belt adapted to be brought into proximity to the drum thereby to grip a portion of the skin being operated upon, a movable frame carrying said belt, means for supporting and guiding said frame to bring said belt to various positions, means for bringing said belt into operative relationship with said drum comprising an inwardly movable transverse bar at the front of the machine over which another portion of the skin extends, and a connection between said transverse bar and the belt carrying frame thereby to stretch the intermediate portion of the skin when pressure is applied to said bar; and means for adjusting the means for supporting and guiding the belt carrying frame thereby to vary the extent of possible engagement of the belt with the periphery of the drum.

WILLIAM B. QUINN.
